UNITED STATES PATENT OFFICE

167,239

TELEVISION PROJECTION UNIT

Victor Trad, Asbury Park, N. J.

Application February 28, 1952, Serial No. 18,709

Term of patent 14 years

(Cl. D56—4)

To all whom it may concern:

Be it known that I, Victor Trad, a citizen of the United States of America, residing at Asbury Park, Monmouth County, New Jersey, have invented a new, original, and ornamental Design for a Television Projection Unit, of which the following is a specification, reference being had to the accompanying drawing, forming a part hereof.

In the drawing:

Figure 1 is a front view in perspective of a television projection unit, showing my new design.

Figure 2 is a rear elevational view of the television projection unit shown in Figure 1.

The bottom surfaces of the projection unit are plain. The side of the projection unit opposite

that shown in Figure 1 is identical in appearance thereto.

I claim:

The ornamental design for a television projection unit, substantially as shown and described.

VICTOR TRAD.
